JOSEPH WALTER FLAGG, OF WORCESTER, MASSACHUSETTS.

SIGNALING APPARATUS FOR MARINE VESSELS.

1,117,176.

Specification of Letters Patent. Patented Nov. 17, 1914.

Application filed February 7, 1910. Serial No. 542,393.

To all whom it may concern:

Be it known that I, JOSEPH WALTER FLAGG, a citizen of the United States, residing at Worcester, in the county of Worcester and Commonwealth of Massachusetts, have invented a new and useful Improvement in Signaling Apparatus for Marine Vessels, of which the following is a specification, accompanied by drawings, forming a part of 10 the same, in which—

Figure 1 represents a diagrammatic view showing contiguous vessels moving in different directions, one of said vessels being equipped with my improved signaling apparatus. Fig. 2 is a side elevation of the signaling apparatus. Fig. 3 is a plan view on a larger scale of the operative mechanism by means of which certain characteristics of the signals, such for example as direction, 20 force, pitch, intervals, etc., may be varied. Fig. 4 is a side elevation of the operative mechanism, a portion thereof, and also the inclosing case therefor, being shown in section, on the line 4—4, Fig. 3. Fig. 5 is a 25 detached sectional view of a portion of the rotating mechanism, whereby the direction of successive signals is varied. Figs. 6, 7 and 8 are detached views, shown in elevation, of a portion of the signal controlling 30 mechanism, each of said figures showing the parts in different positions. Fig. 9 is a plan view in section on the line 9—9, Fig. 5. Fig. 10 is a detached view of a portion of the driving mechanism with the connected 35 latching bar, and Fig. 11 is a detached view of the friction lever 27 with its connected operating mechanism.

My present invention relates to a system of audible signaling especially adapted for 40 marine vessels, comprising a succession of sounds produced by any convenient means, such as a whistle, siren, horn, or the like, and capable of conveying to the hearer certain desirable information relating to the 45 signaling vessel, such as its direction, speed, size, motive power, etc. These results are accomplished in the system forming the subject of my present invention by producing certain variations in the signals rendered by 50 means of any operating mechanism suitable for the purpose. One embodiment of an operating mechanism capable of producing the several variations in the sound signals according to my present invention is here- 55 in shown and described, but I do not confine myself to any special embodiment of the op-

erating mechanism, as the same may be varied as judgment or ingenuity may dictate, or as the conditions of use may render necessary.

The essential feature of my invention consists in conveying to the hearer certain definite information regarding the signaling vessel by means of certain variations in the character of the sound signals. This is accomplished by varying the force or intensity of successive sounds as they are received by the hearer and thereby indicating the position of the signaling apparatus relatively to the direction of the vessel, by determining 60 the pitch of the sounds, by varying the intervals between successive sounds of a given series, by varying the intervals between series, or by the multiplication of certain sounds in the series, as hereinafter described 65 and pointed out in the annexed claims.

Referring to the diagrammatic view shown in Fig. 1, which represents a plan view of three vessels, A denotes the vessel upon which my improved signaling apparatus is installed and B and C the two vessels upon which the signals are being received. The vessels are assumed to be moving in the directions indicated in Fig. 1, the movement of vessel B being directly across the 80 bow of the signaling vessel A, while vessel C is upon the opposite side and passes in a contrary direction to the signaling vessel A. The signaling apparatus is represented upon vessel A at D and the captains or other 85 officers of the vessels B and C are stationed at E and F respectively.

The signaling apparatus comprises a horn 1, preferably arranged in a horizontal plane and having a rotative movement about a 90 vertical axis 2, said axis being indicated in Fig. 2 by the broken line 3, 3. Any suitable mechanism is provided for producing a blast of air or steam through the horn 1. The horn is rotated about the vertical axis by 95 any suitable operating mechanism such as that represented in the accompanying drawings and hereinafter described, or by any other suitable mechanism by which a rotative movement may be imparted to the horn. 100 In the present instance the mechanism employed is adapted to impart an intermittent rotative movement through predetermined arcs with a period of dwell between each movement, said periods of dwell occurring 105 when the mouth of the horn is pointed in one of the five directions indicated by the 110

arrows 4, 5, 6, 7 and 8, Fig. 1. The connection of the horn with the sound producing means is such that a short blast will be emitted at each direction of the horn as indicated by the arrows 4, 5, 6, 7 and 8, whereby the direction of the horn at each period of signaling will bear a certain fixed angular relation to the axial line of the vessel, the signals occurring in directions 4 and 5 being directed toward the larboard side of the vessel and those in directions 7 and 8 toward the starboard side. Of the four signals given upon the opposite sides of the vessel, those at 4 and 8 will be directed toward the stern and those at 5 and 7 toward the bow.

If the sounds produced are uniform at the signaling vessel, they will be varied at the receiving vessel according to the direction of the horn, as it is pointed toward or away from the receiving vessel. In the diagram shown in Fig. 1, if uniform signals are emitted by the horn in each of the five directions, the signal given in the direction 5 will sound much louder upon the receiving vessel C than that in any of the other directions, while that given in the direction 8 will be the faintest; likewise the signal given in the direction 7 will be the loudest and that in direction 4 the faintest when received upon the vessel B. The period of time during which the horn is moving from one direction to the other will constitute an interval between the signals. In the present instance the intervals between signals given in the directions 4, 5, 6, 7 and 8 will be uniform, while the interval between the signals given in the direction 8 and the direction 4 will be twice the length of the other intervals. The long interval will, therefore, occur when the horn is moving from the starboard to the larboard side of the vessel, and the signal given between the two larboard signals in the directions 4 and 5 and the two starboard signals in the directions 7 and 8, or the intermediate signal, will always be directed toward the bow of the vessel. The long interval between the signals in the directions 8 and 4 will always occur as the mouth of the horn is pointed toward the stern of the vessel. These fixed relations of the horn to the axis of the vessel during each individual signal enables persons upon the receiving vessels B and C to determine the direction in which the vessel is moving. An officer upon vessel B, for example, by the greater intensity of sound at the fourth signal after the long interval will be aware not only of the relative position of the signaling vessel to his own vessel, but will also be apprised of the direction in which the signaling vessel is moving, as the signal having the greatest intensity when received upon vessel B will be the first signal upon the starboard side and at a predetermined angle to the axis of the vessel A, said angle being

known to the hearer upon vessel B. The information thus imparted informs the officer upon vessel B that the direction of his own vessel is across the bow of the signaling vessel A. In like manner the officer upon vessel C is informed of the relative positions of the two vessels and of the direction in which vessel A is moving, as the loudest signal of the five in the series heard upon vessel C is that given in the direction of the arrow 5, which is the second larboard signal.

I have devised certain modifications or refinements of operation by which other suitable information may be imparted to officers of receiving vessels, such as motive power, speed, size and other items of information when desired. This information I propose to impart by certain modifications in the pitch of the signals, duration of intervals, multiplication of signals, etc., as hereinafter described.

As previously described, the direction of the bow of the signaling vessel will be determined by the relative force or intensity of the individual signals. By giving to the signals a certain predetermined pitch, the size or tonnage of the vessel may be indicated, a certain pitch being adopted to indicate vessels of five thousand tons or under, another pitch for vessels between five thousand and ten thousand tons, another pitch for vessels between ten thousand and twenty thousand tons and still another pitch for vessels exceeding twenty thousand tons. By varying the rotative speed of the horn about its vertical axis, the intervals between signals can be so changed as to indicate the speed of the signaling vessel. A variation in the interval during which the horn is passing from the position 8 to the position 4, and from the last starboard to the first larboard signal, may be employed to denote the power by which the signaling vessel is propelled, one interval indicating sails and another steam power. Other information may also be conveyed by duplicating any one of the individual signals; for example, a double signal given when the horn is in the direction 6, or toward the bow of the vessel, may indicate that the signaling vessel is drifting, having lost its propelling power. To an officer stationed at E upon the receiving vessel, the force of the first starboard signal at 7 indicates that the course of the signaling vessel is across the bow of the vessel B. A predetermined interval between each two of the signals in the series may indicate that the signaling vessel is moving at a given rate of speed, say ten miles per hour. A predetermined interval between the starboard and the larboard signals, or while the mouth of the horn is passing from the direction indicated by the arrow 8 to that indicated by the arrow 4, may indicate that the signaling vessel is propelled by steam and, by the pre-

determined pitch of the signals, the tonnage of the signaling vessel may be indicated. In addition to the above information, a duplication of the bow signal, or that given in the direction of the arrow 6, may be utilized to indicate that while the vessel is propelled by steam it is not moving under its own power, but drifting. Similarly, a duplication of any one of the other individual signals may be made to convey other information such, for example, as the nationality of the vessel.

To indicate the modifications or refinements in the operation of my signaling apparatus, I have illustrated in the accompanying drawings the operative mechanism which I inclose in a case 9, Fig. 2, said case being shown on an enlarged scale with the cover removed in Fig. 3 and also in Fig. 4 with one side removed on the broken line 4-4, Fig. 3. The horn 1 is mounted upon a hollow spindle 10, journaled in vertical bearings and intermittently rotated and held stationary between each intermittent movement. The driving mechanism comprises a motor spring contained in a case 11 and operating through a train of gears to rotate a shaft 12. The shaft 12 carries a worm 13 which engages a worm wheel 14 attached to a vertical spindle 15. The vertical spindle 15 carries a drum 16 at its upper end and a circular plate 17 provided with a driving tooth 18 which, during each rotation, engages one of the notches 19 upon a plate 20, turning the latter one sixth of a revolution. Between each intermittent rotation of the plate 20, it is held from turning by the engagement of the circular periphery of the plate 17 with one of the concave recesses 21 upon the plate 20, said plates 17 and 20 constituting the well known Geneva stop motion. The plate 20 is attached to the hollow spindle 10 upon which the horn 1 is mounted. Connected with the shaft 12 is a centrifugal governor comprising the weighted balls 22, 22, which are attached to springs 23, 23 midway their length. The outer ends of the springs 23 are pivotally connected with a collar 24 attached to the shaft 12. The inner ends of the springs 23 are pivotally attached to a disk 26, having a spline connection with the shaft 12 by a spline 25. Opposing the outer surface of the disk 26 is a friction lever 27 pivoted at 28 upon a fixed stud 29. Sliding in bearings upon the fixed stud 29 is a vertical rod 30 extended downward through the casing 9 by a link 30^a. A collar 31 is attached to the upper end of the rod 30 and between the fixed bearing and the collar 31 is interposed a spiral spring 31^a, which normally holds the rod 30 in an elevated position. Attached to the rod 30 is a wedge shaped plate 32 which bears against an arm 33 projecting at right angles

from the lever 27. A spring 34 connects the lever 27 with a fixed arm 35, with its tension applied to hold the arm 33 against the edge of the wedge shaped plate 32.

When the speed of the shaft 12 increases sufficiently to throw the weighted balls 22 outward, the disk 26 is drawn against the friction 27, which acts as a brake to check the speed of the shaft 12. By raising and lowering the wedge shaped plate 32, the position of the friction lever 27 may be varied, thereby enabling the operator to control the speed of the shaft 12 and consequently the speed of the connected mechanism by which the rotating horn is driven. Attached to the hollow rotating spindle 10 and below the plate 20 is a disk 36 having a notch 37 adapted to be engaged by the end 38 of a sliding rod 39, which is also provided with an arm 40 adapted to engage a notch 41 in the drum 16, thereby holding the driving mechanism from rotation. The sliding rod 39 is moved to the right to carry its end 38 into the notch 37 and its arm 40 into the notch 41 by means of a compression spiral spring 42 interposed between a fixed stud 43, which forms a bearing for one end of the rod 39, and a collar 44 attached to the rod.

In a bearing carried by the stud 43 is a vertically sliding rod 45, extending downward through the case 9 into position to be depressed by the operator at will, and normally held in a raised position by means of a spiral spring 46 interposed between the fixed bearing of the rod and a collar 47 attached to the rod 45. When the rod 45 is in its raised position, it passes by and intercepts the end of the sliding rod 39, thereby preventing its sliding movement toward the left and the release of the driving mechanism.

The mechanism for withdrawing the rod 39 from the drum 16 and disk 36 comprises a motor spring inclosed in a case 48 and rotating through a train of gearing a shaft 49, which carries a worm 50 engaging a worm wheel 51 attached to a vertical shaft 52, to the upper end of which is attached a disk 53 provided with a radially projecting tooth 54, which contacts during its rotation, in the direction of the arrow 55, with the collar 44 to move the sliding rod 39 in the direction of the arrow 56 whenever the locking rod 45 has been depressed.

The speed of the shaft 49, like the speed of the shaft 12, is controlled by a controlling mechanism which is the duplicate of that applied to the shaft 12 and comprises the weighted balls 57, 57, springs 58, 58, friction disk 59, friction lever 60, vertically sliding rod 61 and wedge shaped plate 62 operating against the right angled arm 63 of the lever 60. The rod 61 is extended downward through the case 9 by means of a link 61^a,

Figs. 2 and 4 enabling the operator to depress the wedge shaped plate 62 against the tension of a spiral spring 64 and thereby vary the position of the friction lever 60 in order to control the speed of the shaft 49.

The hollow spindle 10 is provided near its lower end with lateral openings or ports 65, 66, 67, 68 and 69, Fig. 9 the spaces between said openings being uniform, with the exception of that between 65 and 69 which is double the length of the other spaces. The journal bearing of the hollow spindle is provided with an opening 70 in the plane of the openings in the hollow spindle, said opening 70 communicating with a passage 71 which communicates with a passage 72 at right angles thereto and leads to a source of air or steam under pressure. As the hollow spindle is rotated, each of the five ports are successively brought into alignment with the opening 70, allowing the blast of air or steam transmitted through the passages 72 and 71 to enter the hollow spindle 10 and connected horn 1. Communicating with the passage 72 and transversely thereto is a chamber 73 inclosed in a cylindrical case 74 and containing a series of connected slidable reed boxes, in the present instance three in number, reed 75 in the upper box being in alignment with the passage 72. The reed boxes are connected with the upper end of the case 74 by means of a spiral spring 76, and to the lower end of the reed boxes is connected a link 77 which passes downward through the case 9. Each of the reeds in the three boxes is of different pitch from the others and, as the blast of air or steam is transmitted through the passage 72 to the horn, it will produce a sound corresponding in pitch to that of the reed which, for the time being, is in alignment with the passage 72. In order to change from the reed 75 to the next lower reed at 78, the link 77 is released, allowing the spring 76 to raise the reed boxes a predetermined distance sufficient to bring the reed 78 into alignment with the passage 72 and, in like manner, the lowest reed 79 may be brought into alignment with the passage 72, enabling the sound signals to be given upon the pitch of either of the individual reeds 75, 78 or 79.

The passage 72 is provided with a sliding piston or gate 80 adapted to be moved past the mouth of the passage 71 and cut off the flow of air or steam to the horn. The gate 80 is pivotally connected by a rod 81 with a lever 82, having one end pivoted at 83 to a fixed support and having its free end 84 extending close to the periphery of the drum 16. The pivotal support of the lever 82 is carried by a ring 85 which is rotatable about the axis of the slidable gate 80. From one side of the ring 85 there projects a lug 86 to which a link 87 is pivoted,

extending downward through the case 9 in 65 position to be operated by the attendant.

Projecting radially from the periphery of the drum 16 and midway between its two edges is a pin 88 and near the upper edge of the drum are two similar pins 89 and 90. 70 When the ring 85 and lever 82 have been rocked into the position shown in Fig. 6, the free end 84 of the lever 82 is held below the plane of rotation of the pins 88, 89 and 90. When the free end of the lever is raised, 75 by depressing the link 87, into the position shown in Fig. 7, the free end of the lever will be held in the plane of rotation of the pin 88 and, when the lever is raised into the position shown in Fig. 8, the free end 84 of 80 the lever will be held in the plane of rotation of the two pins 89 and 90. Applied to the lever 82 is a spiral spring 91 which holds the sliding gate 80 at the extreme end of the passage 72, so as not to impede the movement of air or steam through the passage 71 and into the horn 1. Whenever the free end 84 of the lever 82 is raised into the position shown in Fig. 7, it will be struck by the pin 88 during the rotation of the drum 16, 90 thereby swinging the pivoted lever 82 so as to move the sliding gate 80 temporarily past the mouth of the passage 71 to cut off the flow of air or steam therethrough. As soon, however, as the pin 88 has passed the 95 free end of the lever, the spring 91 will restore the sliding gate 80 to its normal position, as shown in Fig. 3. This action of the pin 88 will, therefore, cause a momentary interruption of the current of air or steam 100 through the horn and divide the signal which is being given during that rotation of the drum 16 into two parts, producing a multiple signal. When the lever 82 is raised into the position shown in Fig. 8, it will be 105 contacted twice during the revolution of the drum 16 by the pins 89 and 90, causing two interruptions of the sound and dividing the signal into three parts. The drum 16 is provided with a series of holes 92 adapted 110 to receive the pins 88, 89 and 90 and, by multiplying the number of pins in each plane of holes, the signals can be again subdivided so that, instead of one continuous signal, a succession of short signals may be given. 115 By a suitable arrangement of the pins relatively to the rotative movement of the drum 16, the interruption of the sound may be made to occur either at the middle of the signal, thereby producing two shorter signals, but of equal duration, or nearer the beginning or end of the signal, thereby producing two signals of different duration, with the shorter either preceding or following the longer signal.

The downwardly extending rods and links 30^a, 45, 61^a, 77 and 87 may be operated by a single attendant and, assuming the parts

of the operative mechanism to be in the relative positions shown in Figs. 3 and 4, the operation of the apparatus is as follows:—The attendant depresses the rod 45 and withdraws the upper end from the path of the sliding rod 39, which allows the disk 53 to turn and, by means of its projecting tooth 54, push the sliding rod 39 to the left in the direction of the arrow 56, thereby 10 releasing the drum 16 on the vertical spindle 15 and also the disk 36 on the hollow spindle 10. The withdrawal of the sliding rod 39 permits the driving mechanism for rotating the hollow spindle 10 to be set in motion by the tension of the motor spring 15 in the case 11.

At each revolution of the spindle 15, an intermittent motion of one sixth a revolution is given to the plate 20 by the engagement of the tooth 18 with one of the notches 19. Between each intermittent movement of the plate 20 it is held from rotation by its engagement with the circular periphery of the plate 17. During the stationary position 25 of the plate 20 and hollow spindle 10, one of the ports of the latter will be held in alinement with the opening 70 communicating with the passages 71 and 72 through which the blast of air or steam is communicated to the horn 1. At each rotation of the vertical spindle 15 an intermittent movement will be given to the hollow spindle 10, bringing the next succeeding port into alinement with the opening 70. The space between the ports is doubled between the ports 30 65 and 69, requiring two intermittent movements of the plate 20, after the port 65 has been passed, in order to bring the port 69 into alinement with the opening 70. By this arrangement of the ports in the hollow spindle, five successive signals will be given during each complete rotation of the plate 20, one at each of the first five intermittent movements, the sixth intermittent movement failing to sound a signal as the corresponding 45 port in the hollow spindle is omitted. In attaching the horn to the hollow spindle 10, the mouth of the horn is made to point toward the stern of the vessel during the 50 interval between the two instants that the ports 65 and 69 are in alinement with the opening 70, thereby producing an interval of double length and omitting the usual signal as the mouth of the horn passes the stern of the vessel, but making the intervals 55 uniform between each of the remaining five signals.

After the vertical spindle 15 has made six complete revolutions and the hollow spindle 60 10 has made one complete revolution, both of the notches 41 and 37 will be brought into alinement with the sliding rod 39, which will then be moved to the right by the force of the spring 42, causing the driving mechanism 65 to be again locked and held from rotation.

If the vertically sliding rod 45 be permanently maintained in its depressed position, the next succeeding contact of the tooth 54 against the collar 44 will again move the rod 39 to the left and allow another cycle of five signals to be given. During the rotative movement of the hollow spindle 10, any desired variation may be made in its speed by varying the position of the friction lever 27 relatively to the normal position of the friction disk 26. A decrease in the speed of the hollow spindle 10 will increase the duration of each signal and also the intervals between the signals, requiring a longer time for completing the 70 cycle of five signals. Whatever the interval between any two signals in a cycle of series may be, the interval between the last signal of the series and the first signal of the next succeeding series will be twice that 75 length if the locking rod 39 is permanently held out of engagement with the driving mechanism, but as the rod is again carried into engagement by the spring 42 at the end of each cycle, the length of the long interval 80 can be varied by varying the speed of the vertical shaft 52 so as to allow the driving mechanism to remain locked. The adjustment of the wedge shaped plate 32 by means of the rod 30 will, therefore, determine the period of time required for each 85 cycle of signals and, consequently, both the duration of each signal and the intervals between successive signals of the cycle. The adjustment of the wedge shaped plate 62 by 90 means of the link 61^a will enable the long interval between the starboard and larboard signals to be increased. The adjustment of the pivoted lever 82 by means of the link 87 will enable any one of the signals to be subdivided at will and the number of signals 95 correspondingly multiplied. By the adjustment of the reeds 75, 78 and 79, set at different pitches, the pitch of the signals may be varied, the five signals of each series being 100 all given at a predetermined pitch, or a variation can be made in the individual signals of each series as may be required by any predetermined code, which will enable the 105 different variations to be intelligible upon 110 the receiving vessels.

A code which will adapt the possible variations of my improved system of signaling for practical use may be arranged as desired. I have only suggested in the 115 above description the character of the information which it is possible to convey, and I have shown an operative mechanism capable of producing each of the several variations referred to, although I do not 120 confine myself to the operative mechanism shown and described.

The embodiment of my invention comprises a horn, or other suitable device, preferably arranged in a horizontal plane and 130

6
capable of rotation about a vertical axis, for conveying audible signals produced in any usual and well known manner, such as that produced by air or steam under pressure, with suitable operative mechanism connected therewith to cause a variable rotation of the horn and to produce changes in the pitch of the signals, or a multiplication thereof.

10 I claim,

1. In a signaling apparatus, a sound projecting device, means for rotating said sound projecting device into a series of predetermined positions, automatic means for interrupting said last mentioned means, and means for releasing said interrupting means.

2. In a signaling apparatus, a sound projecting device, automatically controlled means for imparting rotative movement to said sound projecting device, means for interrupting the action of said last mentioned means, and automatically controlled means for releasing said interrupting means.

3. In a signaling apparatus, a sound projecting means, means, comprising a motor, for rotating said sound projecting means into a series of predetermined positions, automatic means for interrupting the action of said motor, and means, comprising a second motor, for releasing said interrupting means.

4. In a signaling apparatus, a sound projecting means, a motor for imparting rotative movement to said sound projecting means, automatic means for controlling the speed of said motor, automatic means for interrupting the action of said motor, a second motor adapted to intermittently release said interrupting means, and automatic means for controlling the speed of said second motor.

5. In a signaling apparatus, a sound projecting means, a motor for imparting rotative movement to said sound projecting means, automatic means for controlling the speed of said rotative movement, means for varying the speed of said rotative movement at will, automatic means for interrupting the action of said motor, a second motor adapted to intermittently release said inter-

rupting means, means for controlling the speed of said second motor, and means for varying the speed of said second motor at will.

6. In a signaling apparatus, means for 55 conveying a blast of steam, sound producing means in the path of the steam, rotatable means in communication with said steam conveying means for causing a series of sounds to be produced by said producing means upon each revolution of said rotatable means, and means, comprising a valve for momentarily interrupting the flow of steam in said conveying means, for dividing each sound into a predetermined number of 60 shorter sounds.

7. In a signaling apparatus, means for conveying a blast of steam, sound producing means in the path of the steam, rotatable means in communication with said steam 70 conveying means for causing a series of sounds to be produced by said producing means upon each revolution of said rotatable means, a valve for momentarily interrupting the flow of steam between said sound 75 producing means and said rotatable means, and means, comprising a series of pins rotated in synchronism with said rotatable means, for operating said valve.

8. In a signaling apparatus, means for 80 conveying a blast of steam, sound producing means in the path of the steam, rotatable means in communication with said steam conveying means for causing a series of sounds to be produced by said producing 85 means upon each revolution of said rotatable means, a valve for momentarily interrupting the flow of steam during the period of each sound, a lever for operating the valve, a plurality of series of pins disposed at pre-determined selected points on said rotatable 90 means, adapted to engage the lever to operate the valve, and means for projecting said lever into the path of a selected series of pins.
